PAPER BOARD BOX

Filed Nov. 12, 1929

FIG. 4.

FIG. 3.

FIG. 1.

FIG. 2.

UNITED STATES PATENT OFFICE

JOHN ERNEST PAGE, OF SYDNEY, AUSTRALIA, ASSIGNOR, BY MESNE ASSIGNMENTS, TO THE GUARDIAN TRUST COMPANY, OF CLEVELAND, OHIO, A CORPORATION OF OHIO, TRUSTEE FOR GIBSON PATENT CONTAINERS, LTD., A CORPORATION OF NEW SOUTH WALES, AUSTRALIA

PAPER-BOARD BOX

Application filed November 12, 1929, Serial No. 406,685, and in Australia April 19, 1929.

This invention relates to paperboard boxes or containers for containing retail quantities of dried fruits, confectionery, and other products, and in particular it relates to boxes 5 in which interfitting but unattached bottom, side, and top members of stiff paperboard are bound together in assembled relation by a wrap of flexible film or fabric material which forms a close fitting envelope but is not glued 10 or otherwise fixed to the paperboard pieces.

Boxes made on this principle are economical for the packer, inasmuch as ready cut sheets of paperboard and the wrap sheets may be kept in flat condition during transport and 15 storage, thereby minimizing space, and the container can be assembled complete in set-up form and ready for packing with speed and facility.

In one known construction of such paper- 20 board boxes a wrap sheet which consists of textile or gauze fabric or tough flexible paper or "cellophane" or like filmy material is stretched flat under one end of the structure and is gathered up and pleated over the sides 25 of the structure, and its marginal portion is creased and pleated down flat over the top end of the structure; and fastening of the whole assembly is effected by fixing an adhesive sticker or seal piece over the converged 30 edges of the wrap sheet.

Box bodies and lids heretofore have also been produced on a similar principle by assembling paperboard side and end pieces without fastening them together, drawing a 35 wrap sheet about them, infolding the edges of the wrap sheet over the side pieces, and forcing a false end piece into the body or the lid thus formed so as to flatten down and stretch the infold of the wrap sheet against the in- 40 terior face of the sides and to secure the edge portions of it under this false end piece. In this type of construction the lid must be made larger in diameter than the body in order that it may be slipped over the body.

45 One of the objects of the present invention is to so modify the known methods of construction as to make it practicable to have the lids identical in size with the bottom end member, in order to facilitate production of 50 both said parts in the same presses and with

rim and end paperboard parts of identical size and flexible wrap sheets of reduced size for the bottom end member.

Another object of the present invention is to economize the area of the wrap sheets; the 55 wrap sheets are the most costly element in the structure; as in most cases material such as silk, or "cellophane", or a costly paper is used in order to procure a desirable finish effect.

This invention also comprehends a container having a bottom end member and a continuous tubular member of paperboard material. The bottom end member may comprise a side wall or rim portion and a bottom portion held assembled together by a wrap sheet. The tubular member, which forms a portion of the body of the container, is forced into the bottom end member and extends above the rim portion any distance 70 convenient and desirable to properly contain the contents. An oversize false bottom insert or piece of stiff paperboard material is forced into the tubular member to bind the tubular member and bottom end member together in 75 firm, set-up, assembly and without the use of glue, staples, or other fastening means. The tubular member, expanded outwardly by the oversize insert piece, firmly clamps the in-turned edge of the wrap sheet between the 80 tubular member and rim portion of the bottom end member. Thus the rim portion and bottom portion of the bottom end member are also securely bound together without the use of glue, staples or other securing means.

85 My container can be manufactured at low cost since no gluing or stapling operation is necessary. The container is especially useful in the packaging of dried fruits, confectionery and food products which are liable to become contaminated from glue, staples or similar securing materials.

90 The invention will be described with more particularly with reference to the accompanying drawing, in which:

95 Fig. 1 is a perspective view of a five-sided container constructed according to the invention;

100 Fig. 2 is an exploded view showing the various parts of the container, A being the

5 false bottom or insert piece, B the side liner or tubular member, C the bottom rim portion, D the wrap sheet shown under the box bottom in the first stage of the assembly, and E the bottom portion set down on the wrap sheet D. The ends of the strip of pasteboard which forms the rim C may be lapped and conjoined by a tongue and slot fastening 10, or they may be abutted and secured together 10 by a pasted on paper lap 11, as shown in the case of the tubular member B;

Fig. 3 is a perspective view of the lid; and

Fig. 4 is an exploded view of the lid parts comprising wrap sheet F, top G, rim H, and 15 false end K.

For the wrap sheets, thin silk or like fabric, parchmentized paper, or a synthetic substance such as "cellophane" is used. Whatever the material, it must be such that when 20 creased and pleated and drawn taut it will lie flat and close against the pasteboard structure, and it must have sufficient strength to bind the pasteboard parts and maintain the shape and integrity of the bottom end member. The bottom end member obtains its stiffness from the interfitting paperboard elements and it obtains its integrity from the wrap sheet. When the wrap sheet is made of transparent material, printing applied to 25 the pasteboard sides or ends will be visible through the wrap.

The containers may be made in any practicable shape; they may be triangular, rectangular, polygonal, circular, or ovate, to suit 30 any particular demand, and either one or both ends may be apertured to offer a view of the contents through the flat stretched part of the wrap sheet (if it be transparent).

The structural members comprising the 40 container (other than the wrap sheet) are formed of pasteboard, paperboard, fibreboard or like materials, of appropriate stiffness, having regard to the size and shape of the box. These structural members comprise 45 an end or bottom portion E, a continuous rim portion C with tangs 14 on its bottom edge forming the bottom end member of the container. A continuous side liner or tubular member B, preferably with tangs 15 on 50 its bottom edge, is telescoped into the bottom end member. A false bottom or oversize stiff insert piece A is then forced into the tubular member, expanding the same into frictional binding engagement with the rim portion C. 55 The lid for the container may comprise an end G, a continuous side H with tangs 17 on its top edge, and false end K.

The paperboard pieces of which the body and the lid sides are made are notched along 60 one edge and creased intermediate the notches to form tangs (14, 15 and 17). These tangs are bent at right angles to set against the ends E and G respectively; they are embraced between the respective ends E and G and the 65 insert pieces A and K when the parts are

assembled. The rims C and H when bent to the desired shape, are conjoined at their meeting ends either by a cemented tab 18, Fig. 4, over a butt joint, or alternatively by an interlocking tang and slot arrangement shown at 10, Fig. 2, in a lapped joint. Similarly, the ends of the tubular member B may be joined together by the cemented tab 11 to form a continuous side or body wall. The side liner or tubular portion B of the container body is 70 made to extend any desired distance above the rim portion C.

A deep former block having the internal plan dimensions and shape of the box is used 75 to facilitate assembling of the parts.

In building a body the wrap sheet D is first set down on a table symmetrically over an aperture therein which is the same in shape and external plan dimensions as the box to be produced; over the wrap sheet D the bottom piece E is set down in register with the table aperture.

Then a strip of pasteboard is notched along 80 one edge and its ends butted and secured together by a lap of thin tough paper glued over the joint. The length of this strip is the peripheral measurement of the box side, and the notchings are shaped and spaced appropriately to the plan shape of the box to permit the strip to be bent to that shape. Thus, in the case of a cylindrical box there would be a large number of V-notches in close order, to facilitate the bending of the strip to form a ring, and in the case of a rectangular box there would be four right angle notches spaced apart symmetrically, one for each corner. Optionally the ends of this strip may be connected by a tongue and slot lapped joint 85 as shown at 10, but it is preferred to use the butt joint with paper lap fastenings. When 90 its ends are connected the strip becomes a continuous band. The tangs 14 on the band which intervene between the notches are bent inward, and the band is then slipped up onto the block with these tangs inbent under the block. The block is then forced down, so as to "draw" the wrap sheet with the bottom piece E, lying on it, down through the aperture in the table. The block corresponds in 95 plan shape with the table aperture and with the box plan, but the table aperture is a little larger than the block to offer clearance for the thickness of the band and the skirt of the wrap sheet which is pleated up over the band.

The part of the wrap sheet which is not 100 directly over the table aperture is thus caused to be drawn up and pleated and pressed flat about the rim portion C which is formed by the band. The former block is now withdrawn, and the upstanding marginal portions of the wrap sheet are then infolded, as at 12, over the rim portion C. The side liner or tubular member B is then forced into the body 105 and finally the false bottom or oversize insert piece A is pushed down into place. In this 110

operation the infolded part 12 of the wrap sheet is drawn down taut and pressed flat against the interior face of the rim portion C, and is embraced tightly between the rim portion C and the tubular member B, and the indent tangs 15 on the bottom edge of the tubular member B are secreted between the insert piece A and the bottom portion E. The insert piece A, inserted after the tubular member B has been forced into the bottom end member, struts or expands the bottom part of the tubular member B outwardly against the rim C, thus frictionally binding the tubular member B and the bottom end member together in fixed engagement, without the use of glue, staples, or other fastening means. The wrap sheet D need not be larger than is necessary to provide sufficient skirt to infold over the rim C, as shown at 12, Fig. 2, so that it will be secured effectively between the interior face of the rim C and the exterior face of the tubular portion B.

In building the lid, the same table and the same assembling block are used. The top piece G, insert piece K, and rim portion H, are identical with the corresponding parts in the bottom end structure. The wrap sheet covering the bottom end member need be no larger than is necessary to leave a liberal infold 12 on the inside face of the rim C, but the lid inwrap 13 must be large enough to line the lid sides H and to underlie the insert piece K. The lid wrap sheet F is set down on the apertured table, the end piece G superposed on it in register with the table aperture below, the block, carrying the rim portion H with its tangs 17 infolded, is pressed down, and the whole assembly is forced through the table aperutre, thereby causing the wrap sheet to be drawn up and pleated over the exterior of the lid side. The block is now retired, and the upstanding margin portion of the wrap sheet is infolded as at 13 over the lid rim H with margin 13 α of the wrap lying on the interior face of the top piece G. The insert piece K is then forced into the lid so as to draw down, stretch and pleat the infolded portion at 13 over the interior face of the rim H, embracing the edge portions 13 α of the wrap between the end G and the false end K.

In boxes according to this invention a wrap sheet of smaller area than was previously necessary can be used. The economy in cost of wrap material thus effected is of great practical importance as that material is the most costly element in the structure.

What I claim as my invention and desire to secure by Letters Patent is:—

1. In a container, a bottom end member comprising an annular side wall having in-turned members at an end, a bottom piece disposed outside of and overlying said members, a wrapping of flexible material covering said bottom piece and side wall and being tucked

down within said side wall, a body comprising a tubular member with inturned members at an end, said body being telescoped within the side walls of said bottom end member to firmly hold said wrapping therebetween, and an insert piece inserted within said tubular member to hold said tubular member firmly against said tucked-in wrapping and against the side wall of the bottom end member.

2. A container of the character described, comprising, a continuous tubular member of fibreboard material forming a body portion of the container, a bottom end member comprising a bottom portion and a side wall portion telescoped over one end of said tubular member, said tubular member having tang portions projecting inwardly and resting on the inside face of said bottom end member, and a stiff oversize insert member within said tubular member, said insert member having its peripheral edge pressed against the tubular member whereby the tubular member and the bottom end member are secured together in frictional binding engagement to provide a complete set up container assembled without the use of further securing means.

3. A container of the character described, comprising, a continuous tubular member of comparatively stiff paperboard material forming a body portion of the container, a bottom end member comprising a bottom portion and a rim portion telescoped over one end of said tubular member, said tubular member having tang portions projecting inwardly and resting on the inside face of said bottom end member, and an oversize stiff insert member within said tubular member, said insert member having its peripheral edge pressed against the tubular member to hold said tang portions seated closely against the inside face of the bottom portion of said bottom end member, said insert member also pressing the tubular member against the rim portion of said bottom end member whereby the tubular member and the bottom end member form a complete container secured together in firm assembly by frictional binding engagement only.

4. A container of the character described, comprising, a continuous first wall portion formed from relatively stiff paperboard material, a separate second wall portion surrounding said first wall portion, said first wall portion extending a substantial distance beyond said second wall portion and having elements projecting inwardly, and means including a stiff insert member pressed against said elements and also pressed against said first wall portion to frictionally bind said first wall portion and said second wall portion in firm fixed assembly without the use of further securing means.

5. A container embodying a bottom end member, said bottom end member having an

upstanding rim portion, a continuous tubular member of paperboard material forming a body portion of the container, said tubular member having its lower end within said rim 5 and resting on the bottom portion of said bottom end member, said tubular member having a series of free end tangs extending inwardly and resting on said bottom portion, and a stiff oversize insert piece forced down 10 into said tubular member and against said tangs so as to expand said tubular member outwardly against the inner face of said rim portion and bind said tubular member and bottom end member in fixed assembled 15 relationship without the use of other securing means.

6. In the production of containers, these steps which include providing a continuous tubular member of stiff paperboard material 20 with an end series of longitudinal foldable tangs, inserting the lower open end of said tubular member into a separate exterior bottom end member, said bottom end member having a bottom portion and an upstanding 25 annular rim portion, said tangs being bent inwardly into the open end of the tubular member and positioned to rest on the end portion of the bottom end member, and with the lower end of the tubular member snugly 30 surrounded by said rim portion, inserting a stiff oversize insert piece through the open upper end of said tubular member and forcing the same down into said tubular member tightly against said tangs, and with the peripheral edge of the insert piece tightly engaging the surrounding tubular member so 35 as to expand the same against the surrounding rim portion and frictionally bind said tubular member and bottom end member together in fixed assembled relationship without the use of further securing means.

In testimony whereof I affix my signature.
JOHN ERNEST PAGE.
